HEATER

Henry J. De N. McCollum, Chicago, Ill.; Thelma McCollum executrix of said Henry J. De N. McCollum, deceased

Application June 5, 1943, Serial No. 489,765

10 Claims. (Cl. 126—116)

My invention relates to heaters and more particularly to heaters of the internal combustion type commonly used to heat cabins or other enclosed spaces in aircraft, or for other similar purposes.

In internal combustion heaters of the kind to which my invention pertains, it is common to use electrical ignition means for igniting a mixture of fuel and air supplied to the heater. Such electrical ignition means is ordinarily energized from a battery or other outside source of electrical energy. In certain installations it is undesirable to connect the heater with such an outside source of electrical energy and an object of my invention is to provide an internal combustion heater having an electrical ignition system which does not require an outside source of electrical energy.

Another object of my invention is to provide an internal combustion heater wherein the same force which is utilized to force ventilating air through the heater is also utilized to operate an electrical ignition system including electrical generating means.

Another object of my invention is to provide a new and improved internal combustion type of heater having its own electrical generating and ignition means and which is compact, light in weight, efficient, and inexpensive.

Other objects and advantages will become apparent as the description proceeds.

In the drawings:

Fig. 1 is a longitudinal, vertical section through a heater embodying a preferred form of my invention;

Fig. 2 is a transverse, sectional view taken on the line 2—2 of Fig. 1;

Fig. 3 is a transverse, sectional view taken on the line 3—3 of Fig. 1;

Fig. 4 is a partial, longitudinal section showing a modified form of my invention in which I utilize a variable pitch fan for driving a generator;

Fig. 5 is a side view partly in section showing a form of my invention using a variable pitch fan;

Fig. 6 is a longitudinal section through the variable pitch fan control mechanism of the embodiments of Figs. 4 and 5; and

Fig. 7 is a partial, transverse section taken on the line 7—7 of Fig. 6.

The heater shown in Figs. 1 to 3 of the drawings comprises a cylindrical casing 10 having a tapered inlet end 12, adapted to be supplied with ventilating air by a ram, blower, or any other suitable means. A combustion chamber 14 is lo-

cated in the casing 10 and discharges hot products of combustion into the longitudinal passages 16 of a cylindrical heat exchanger indicated generally by reference numeral 18. The righthand end of the heat exchanger 18 is closed by a plate 20 having a central opening 22 in communication with an exhaust pipe 24 through which the cooled products of combustion are discharged to atmosphere.

10 The heat exchanger 18 has a corrugated shell 26 of stainless steel, or other suitable material, and fins 28 have their bases located in folds in this shell 26, as best shown in Fig. 2. Those portions of the fins 28 which project radially outward of the shell 26 are slotted as indicated at 30 in Fig. 1 and project into the ventilating air passage 32 formed between the shell 26 and casing 10 to transmit heat from the hot products of combustion to this ventilating air.

15 20 A muffler 34 is located in the heat exchanger 18 and comprises a sheet metal cylinder 36 closed at its ends by sheet metal plates 38 and 40. A disc 42 of heat insulating material is attached to the plate 38 to protect this end of the muffler 25 from the intense heat of the combustion chamber and the hot gases issuing therefrom. Partitions 44 divide the muffler into compartments which are filled with sound absorbing material, such as glass wool or stainless steel wool, and a row of openings 48 forms acoustic couplings between each compartment and the gas passages 16.

25 30 Part of the air which has passed over the fins 28 is diverted into the pipe 50 leading to a Venturi tube 52. A jet 54 discharges fuel, such as gasoline, 35 into the throat of this Venturi tube, this jet being connected to any suitable source of fuel supply by a pipe 56. The mixture of fuel and air formed in the Venturi tube 52 is delivered to an induction pipe 58, having a discharge end 60 located in the combustion chamber 14 and so positioned as to deliver the combustible mixture in a direction tangential to the circular wall of this combustion chamber. A housing 62 40 attached to the combustion chamber provides a pocket 64 for a spark plug 66 which serves to ignite the fuel and air mixture delivered to the combustion chamber. This pocket connects with the interior of the combustion chamber by way of an inlet opening 68 and an outlet opening 70. 45 50 55 A ring 72 serves to direct liquid fuel delivered to the combustion chamber into the pocket 64. Current for the spark plug 66 is provided by a high tension alternator 76 supported in a sheet metal frame 78, mounted in the forward end 55 of the casing 10. A single wire 80 connects the

alternator 16 with the spark plug 66, as both the spark plug and alternator are grounded through the heater casing. The alternator 16 is driven by a propeller 82 located in the tapered inlet 12 and rotated by the inflowing air delivered by the ram or other suitable air supply means. A high tension magneto with a suitable circuit breaker could be used in lieu of the alternator, if desired.

When the heater is operating, the air entering the inlet or lefthand end of the casing rotates propeller 82 and drives alternator 16 to create a spark across the gap between the terminals of the spark plug 66 and these sparks ignite and maintain combustion of the mixture of fuel and air delivered to the combustion chamber by the induction tube 58. The hot products of combustion flow from the open or righthand end of this combustion chamber into the gas passages 16 and give up their heat to the shell 26 and fins 28 of the heat exchanger 18. The cooled products of combustion pass through the opening 22 in plate 20 and flow through exhaust pipe 24 to atmosphere.

The air supplied to the heater by the ram or blower absorbs some heat from the walls of the combustion chamber 14 and additional heat from the heat exchanger as this air flows lengthwise of the passage 32. Most of this heated air is utilized as ventilating air to heat the airplane cabin or other space to be heated and passes from the tapered outlet end 84 of the casing 10 either directly into the space to be heated or into a duct system leading to selected outlet located in the same or different spaces to be heated.

A small portion of the heated air is diverted into Venturi tube 52 where it mixes with fuel supplied by jet 54 to form a combustible mixture. This combustible mixture flows through induction tube 58 to the combustion chamber where it is ignited by the spark plug 66. The tangential arrangement of the outlet end 60 of the induction tube tends to create a ring of flame in the combustion chamber and this ring of flame cooperates with the spark plug 66 in maintaining combustion. However, since the spark plug continues to operate as long as the heater is in operation, this spark plug alone is sufficient to maintain continuous combustion.

From the foregoing it will be apparent that I have provided a simple, inexpensive, light weight, compact and efficient heater which is entirely independent of any outside source of electrical energy to operate its electrical ignition means. Such a heater may, therefore, be located in places where no outside source of electrical energy is readily available or where it would be disadvantageous to provide wiring to connect the heater with such an external source of current.

I wish particularly to point out that the alternator or other current generator is so located that it is protected against the heat of the combustion chamber and the gas passages leading therefrom. Furthermore the propeller for operating this alternator is located in a contracted portion of the casing where the rate of air flow is relatively great and where the density of the air is a maximum because this air has not yet been exposed to the heat of the combustion chamber and heat exchanger.

In the embodiment of Figs. 1 to 3, inclusive, the propeller and alternator continue to operate as long as ventilating air is supplied to the inlet end of the heater casing. The propeller 82 offers little resistance to the flow of air through the casing and for most purposes it is not objection-

able to have this propeller and alternator operate continuously while the heater is in use. In certain installations, however, the slight resistance offered by the propeller to air flow through the casing might be objectionable or it might be desirable to discontinue alternator operation to prevent magnetic or other electrical interference or for other reasons it might be desirable to render the alternator inoperative as soon as the heater has attained normal operating conditions. In the modified structures of Figs. 4 to 7, inclusive, I have shown means for automatically discontinuing alternator operation as soon as the heater attains normal operating temperature.

In Fig. 4, the alternator 16 is driven by a propeller 82 having adjustable blades 100 which may be shifted from the operating position shown in this figure to positions in planes passing through the axis of the propeller and alternator so that only the edges of the blades are directly exposed to the flow of ventilating air through the casing. In this form of my invention, the combustion chamber is provided with one or more re-igniters 102 to insure maintenance of combustion in the heater after the alternator 16 has ceased to operate.

In the particular embodiment shown, the propeller blades 100 are pivoted in the propeller hub and are automatically shifted between operative and inoperative position in response to variations in heater temperature. When the heater is cold, the propeller blades assume the operative position shown, but after the heater has been started and reaches operating temperature, these blades are automatically shifted to inoperative position wherein they cease to drive the alternator and offer substantially no resistance to air flow through the heater casing. Since automatically controlled fans of this general type are in commercial use for other purposes, a relatively brief description of the operating mechanism for such a propeller will suffice.

As best shown in Figs. 6 and 7, each blade 100 may comprise a flat tapered strip of sheet metal or other suitable material supported in a shaft 104 rotatably mounted in bearings provided by the propeller hub 106. Each shaft 104 carries a gear 108 meshing with the ring-like teeth formed on the reduced extension 110 of a piston 112. The piston 112 is slidably mounted in fluid-tight relationship in a cylindrical extension 114 of the propeller hub 106. The piston 112 is urged to the right by a spring 116 resting on a spring seat 118 adjustably mounted in the cover plate 120 of the propeller hub 106. The spring seat 118 has a wrench receiving portion 122 to facilitate adjustment of this spring seat to vary the tension of the spring 116.

The propeller hub is mounted on the alternator shaft 124 to which it is attached by a set screw 126 or in any other suitable manner. This shaft has a reduced end 128 which extends through the piston 112 and its extension 114 and is slidably received in the bore 128 of the spring seat 118. The piston 112 is preferably provided with a pin 130 to limit movement of this piston under the force of spring 116. This pin 130 serves to determine the full operative position of the propeller blades 100.

The piston 112 is moved to the left by the expansion of fluid in a bulb 132, illustrated in Fig. 4 as being attached to the end wall of the combustion chamber 14. A pipe 134 connects this bulb with a passage 136 formed in a sleeve 138 which constitutes an extension of the housing of

the alternator 76'. The passage 136 communicates with the annular groove 140 in the alternator shaft 124 and this groove in turn communicates with a longitudinal passage 140 by way of drill hole 142. The other end of the passage 140 communicates with the interior of the cylinder 114 through a cross bore 144 in the shaft 124.

When the heater is not operating, the fluid in the bulb 132 is cool and contracted so that the spring 116 holds the piston 112 and blades 100 in the operative position shown in the drawings. If it is desired to operate the heater, ventilating air is directed into the heater supply pipe 146 from a ram or any other suitable source of air supply and rotates the propeller 82', thereby driving the alternator 76'. This alternator supplies current to the spark plug 66 and ignites combustible mixture delivered to the combustion chamber 14 through the induction pipe 58. After the heater has been in operation a sufficiently long time to attain normal operating temperature, the fluid in the bulb 132 heats up and expands and moves piston 112 to the left, thereby shifting the propeller blades 100 so that they lie in planes passing through the axis of the shaft 124. This renders the propeller inoperative and also causes it to offer a minimum resistance to air flow through the heater. Thereafter combustion is maintained by the re-igniter 102. In case ignition should fail in the heater for any reason, the resulting cooling of the bulb 132 will permit spring 116 to return the propeller blades to operative position, thereby driving the generator and re-starting the heater operation.

The modification shown in Fig. 5 is the same as that of Fig. 4, except for the position of the temperature responsive control bulb 132. In Fig. 4, this bulb is illustrated as being attached to a wall of the combustion chamber and responsive to the temperature of that chamber, whereas in Fig. 5 the bulb 132 is placed in the duct 150 which conducts the heated ventilating air to the space or spaces to be heated. A pipe 134 connects this bulb with the blade controlling mechanism so that the position of the propeller blades is dependent upon the temperature of the ventilating air in the duct 150. After the heater has been in operation a short time, the ventilating air will be heated sufficiently to cause the propeller blades to assume their inoperative position and the alternator 76' will remain idle as long as the heater continues to operate in a normal manner.

Except for the automatic mechanism for shifting the propeller blades, the modifications of Figs. 4 and 5 may be identical with that of Figs. 1 to 3. The particular control mechanism for rendering the propeller blades operative or inoperative is to be considered as illustrative only, as any other suitable type of temperature responsive propeller may be substituted for the one shown in the drawings. Some of the fans of this general type use stationary bimetallic blades which change their curvature with variations in temperature. Similarly constructed propellers could be used in lieu of the type shown, but where propellers with bimetallic blades are used it would ordinarily be preferable to place a propeller and alternator in the outlet duct 150 which would have the disadvantage of subjecting the alternator to higher temperatures and for most purposes the arrangements shown in Figs. 4 and 5 would be preferable.

It is to be understood that my invention is not limited to the particular details shown and described herein, but may assume numerous other forms. The combustion chamber, heat ex-

changer and muffler shown herein are claimed in my co-pending applications, Serial Nos. 477,080, filed February 25, 1943; 476,266, filed February 18, 1943; and 478,259, filed March 6, 1943; and other types of combustion chambers, heat exchangers and mufflers may be used in lieu of the particular ones shown herein.

I claim:

1. An internal combustion type of heater, comprising a combustion chamber, means for supplying a combustible mixture thereto, a heat exchanger receiving hot products of combustion from said combustion chamber, a casing surrounding said combustion chamber and heat exchanger, said casing having a tapered inlet adapted to be connected to a ram or blower, a propeller mounted in said tapered inlet, a high tension alternator driven by said propeller, and a spark plug supplied with current by said alternator and serving to ignite combustible mixture in said combustion chamber.
2. A heater of the class described, comprising a combustion chamber, means for delivering a combustible mixture thereto, a spark plug for igniting said mixture, a heat exchanger receiving hot products of combustion from said combustion chamber, a cylindrical casing enclosing said combustion chamber and heat exchanger, said casing having an inlet adapted to be connected to a source of air under pressure, electrical generating means located in said casing and connected to said spark plug, and a propeller in said casing for driving said generating means, said propeller being rotated by air flow through said casing.
3. A heater of the class described, comprising a combustion chamber, a heat exchanger receiving hot products of combustion from said combustion chamber, means for delivering a combustible mixture to said combustion chamber, a casing enclosing said combustion chamber and heat exchanger and having an inlet end for ventilating air, an electrical igniter for said combustion chamber, and electrical generating means connected to said igniter, said electrical generating means being located in said casing ahead of said combustion chamber and heat exchanger, and a propeller for said generating means driven by air flowing through said casing.
4. A heater of the class described, comprising a combustion chamber, a heat exchanger connected thereto, a casing enclosing said combustion chamber and heat exchanger and having an inlet end adapted to be connected to a source of air under pressure, an electrical igniter for said combustion chamber, an electrical generator for said igniter, and a motor located in said casing for driving said generator, said motor being operated by air flow through said casing.
5. A heater of the class described, comprising a combustion chamber, a heat exchanger connected thereto, a casing enclosing said combustion chamber and heat exchanger and having an inlet end adapted to be connected to a source of air, an electrical igniter for said combustion chamber, a generator for supplying current to said igniter, an air driven motor located in said casing for driving said generator, and means for rendering said motor inoperative when said heater is operating normally.
6. A heater of the class described, comprising a combustion chamber, means for supplying combustible mixture to said chamber, an electrical ignited for said mixture, a generator for supplying current to said igniter, a propeller for driving

said generator, and means responsive to temperature variations of said combustion chamber for stopping the operation of said propeller and generator when the heater attains normal operating temperature.

7. A heater of the class described, comprising a combustion chamber, means for supplying combustible mixture thereto, an electrical igniter for said combustion chamber, a generator for supplying current to said igniter, a propeller responsive to the temperature of said heater, said propeller being connected to said generator for driving the same only when current is needed to ignite said mixture, and temperature response means responsive to the temperature of said combustion chamber for controlling the operation of said propeller.

8. A heater of the class described, comprising a combustion chamber, a heat exchanger receiving hot gases from said combustion chamber, means for circulating air over said heat exchanger, an igniter for said combustion chamber, a re-igniter for said combustion chamber, a generator for supplying current to said igniter, an air operated means for driving said generator, said air operated means including automatic control

mechanism for rendering said means inoperative when said heater attains normal operating temperatures.

9. A heater of the class described comprising a casing, a combustion chamber located in said casing, said casing having an inlet adapted to be connected to means for directing air therethrough, a propeller driven by air flowing through said casing, ignition means for said combustion chamber operated by said propeller, and means for rendering said propeller inoperative when said combustion chamber reaches a predetermined temperature.

10. A heater of the class described, comprising a casing, a heat exchanger located in said casing, said casing having an inlet adapted to be connected to a source of air supply, a combustion chamber for supplying hot gases to said heat exchanger, ignition means for said combustion chamber, a propeller operated by air flow through said casing for operating said ignition means, and means for rendering said propeller inoperative when the air leaving said heat exchanger attains a predetermined temperature.
